UNITED STATES PATENT OFFICE.

WILLIAM M. HENDERSON, OF STEELTON, PENNSYLVANIA.

MOVABLE-POINT CROSSING.

No. 898,645.

Specification of Letters Patent.

Patented Sept. 15, 1908.

Application filed October 2, 1907. Serial No. 395,612.

To all whom it may concern:

Be it known that I, WILLIAM M. HENDERSON, citizen of the United States, and resident of Steelton, Dauphin county, State of Pennsylvania, have invented certain new and useful Improvements in Movable-Point Crossings, of which the following is a full, clear, and exact description, reference being had to the accompanying drawings, of which—

10 Figure 1 is a plan view of a movable point crossing, showing my invention applied thereto. Fig. 2 is an enlarged plan view of one of the main track-rails embodying my invention; showing the hard-metal wear-piece, 15 constituting the "knuckle" thereof. Fig. 3 is a section on the line $v-v$, Fig. 2; Fig. 4, a section on the line $x-x$, Fig. 2; Fig. 5 a section on the line $y-y$, Fig. 2, and Fig. 6 a section on the line $z-z$, Fig. 2.
20 This invention relates to the track-rails of movable point crossings, the object being to provide, at the knuckles of said track-rails, a hard-metal wear-piece of novel construction, whereby a strong and efficient structure 25 is secured, and the life of the rails materially lengthened.

To this end the invention consists in cutting away the head of the track-rail for some distance on each side of the "knuckle", and 30 securing to the web of said track-rail a hard-metal wear-piece having a head portion taking the place of said cut-away rail-head; the 35 said hard-metal wear-piece forming the usual apex or knuckle at a point adjacent the points of the movable point rails.

In the drawings, 1 designates the main or track-rail bent to form the usual knuckle, 2. The head of the said track-rail is cut away and removed for some distance on both sides 40 of the knuckle, but the web, 3, and the base, 4, remain intact. Replacing said cut-away portion of the head of the track-rail, 1, is a corresponding portion, 5, of a hard-metal block or piece, 6, said head forming portion, 5, resting upon and being supported by the web, 3, of the track-rail, 1. The hard-metal block, 6, is also provided with a web portion, 8, extending downwardly therefrom on the outer side of the track-rail, and its lower edge 50 supported upon the base of the rail. The said web, 8, and web, 3, of the track-rail are secured together by suitable bolts, 9. The inner edges of the said hard-metal block, 6, are in line with the gage lines of the track- 55 rail, as seen in the drawings, said edges meeting at an apex, to form the usual knuckle, 2.

The hard-metal block, 6, is provided, at each end, with an extension, 10, comprising head and web portions, 11 and 12, (Figs. 5 and 6), the head portion thereof being fitted to and 60 abutting against the outer side of the track-rail, and the web being secured to the track-rail web by the bolts, 9. The ends of the head portions 11 of the extensions 10 are beveled downwardly, to form pick-ups for 65 guttered wheels; that is, wheels having false flanges worn on the outer edge thereof.

It will be seen that by maintaining the web and base of the track-rail integral throughout the entire length of the hard-metal block 70 or piece, and supporting the same thereon and securing it thereto, a very strong and efficient structure is attained, at a minimum expéñse; the rolled metal rail affording an excellent support and reinforcement for the 75 hard - metal block, 6, which is usually a casting.

Having thus described my invention, I claim as new and desire to secure by Letters Patent:—

1. In a movable point crossing, a track-rail bent to form the usual apex or "knuckle", and having its head cut away and removed on both sides of said knuckle, the hard metal piece having the head portion replacing the 85 said cut away portion of the track-rail, said hard-metal head portion resting upon and being supported by the web of the track rail, together with means for securing said track rail and hard-metal piece together, substan- 90 tially as set forth.

2. In a movable point crossing, a track-rail bent to form the usual apex or "knuckle", and having its head cut away and removed on both sides of said knuckle, the hard-metal 95 piece having the head portion replacing the said cut-away portion of the track rail, said hard metal head portion resting upon and being supported by the web of the track rail, the web on said hard-metal piece whose lower 100 edge is supported on the base of the rail, together with the bolts securing said webs together.

3. In a movable point crossing, a track-rail bent to form the usual apex or "knuckle", 105 and having its head cut away and removed on both sides of said knuckle, the hard-metal piece having the head portion replacing the said cut-away portion of the track-rail, said hard-metal head portion resting upon and 110 being supported by the web of the track rail, said hard metal piece being provided with

the end extensions comprising head and web portions, the said head portions being beveled downwardly at their free ends to constitute pick-ups for guttered wheels, together with means for securing said track-rail and hard-metal piece together, substantially as set forth.

In testimony whereof, I have hereunto affixed my signature.

WILLIAM M. HENDERSON.
